COMPARTMENTED PLATE

Arthur M. Grossman, 776 Glenmont, Los Angeles, Calif.

Filed Oct. 13, 1961, Ser. No. 67,061

Term of patent 14 years

(Cl. D44—15)

FIG. 2.

FIG. 3.

*FIG. 4.FIG. 5.FIG. 6.*FIG. 1 is a top plan view of a compartmented plate embodying my new design;

FIG. 2 is a front elevational view thereof;

FIG. 3 is a right side elevational view thereof;

FIG. 4 is a bottom plan view thereof;

FIG. 5 is a cross-sectional view along the lines 5—5 of FIG. 1; and

FIG. 6 is a cross-sectional view along the lines 6—6 of FIG. 1 thereof.

The essential features of my design are shown in full lines.

I claim:

The ornamental design for a compartmented plate, as shown and described.
